JOINT FOR PAVEMENTS

William E. White, Bethlehem, Pa., assignor to
 Kalman Steel Corporation, a corporation of
 Delaware

Application December 5, 1934, Serial No. 756,054

17 Claims. (Cl. 94—18)

My invention relates to expansion joints for concrete pavement.

One object of the invention is to provide an expansion joint for a concrete structure or pavement of such construction that the surface of the adjoining sections of the structure will be retained substantially in alignment under all conditions.

Another object of my invention is to provide an expansion joint structure with offset portions of such construction that the sections of the concrete structure on opposite sides thereof are interlocked against vertical displacement.

The novel features of my invention will be more fully understood from the following description and claims taken with the drawing in which

Fig. 1 is a top plan view of a section of a pavement structure illustrating my invention.

Fig. 2 is a sectional view of the structure taken along line 2—2 of Fig. 1.

Fig. 3 is an enlarged view of a section of the structure taken along line 3—3 of Fig. 1.

Fig. 4 is a perspective view of a section of the strip.

Referring to the drawing, 15 designates a pavement structure provided with an expansion joint 16 embodying my invention. The structure 15 comprises adjacent pavement sections which are shown in the drawing as concrete slabs 17 and 18 having a strip 19 inserted in the joint intermediate the slabs 17 and 18 to provide means to allow the expansion of these slabs. The strip 19 may be of any well known compressible material, such as cork, fibre, asphaltum or the like.

The strip 19, as shown, comprises substantially straight upper and lower portions 20 and 21 respectively. The upper portion 20 of the strip extends a substantial distance below the surface of the pavement. The lower portion 21 of the strip is provided with a plurality of undercut recesses 22, the walls of which converge toward the bottom of the strip and thereby provide dovetail slot adjacent the bottom thereof.

Extending laterally from the side of the strip adjacent the recesses 22 are hollow projections 23 which in cross section are of substantially the same shape as the recesses 22. Each of these projections 23, as shown in Fig. 4 of the drawing, comprises a metallic member 24 having end flanges 25 and 26, respectively, and a top portion 27, which form the ends and top, respectively, of the projection 23, and a member 28 of the shape, size and of the same material as the cut out portions of the strip forming the recesses 21 which

forms the outer face of the projection 23, and is shown substantially parallel to the strip proper.

In the construction of a pavement the strips 19 are positioned on the road bed at the proper distance apart so that the necessary joints 16 may be provided in the pavement and the concrete is poured to form slabs such as 17 and 18 on each side of the joint. Due to recesses 22 in the strip 19 and the hollow projections 23 projections 29 are provided on the slab 17 which converge towards the bottom thereof and recesses 30 are provided on the slab 18 which cooperates with the projections 29 to provide interlocking means between the slabs 17 and 18 so as to retain the upper surfaces of the slabs 17 and 18 substantially in alignment while permitting laterally slidable movement of the slabs with reference to each other.

The slabs 17 and 18 are preferably formed so that the projections 29 are on the near side of the joint, and the recesses 30 are on the far side of the joint, the direction of traffic over the pavement shown being in the direction of the arrow so that the slab 18 which is on the far side of the joint will be supported partially by the projections 29 on the slab 17 when the load is transmitted to said slab 18 by traffic passing over the pavement.

From the foregoing it will be obvious to those skilled in the art that I have devised an improved expansion joint structure which is simple in construction and which effectively retains adjoining slabs in alignment and at the same time permits lateral movement due to expansion and contraction.

While I have shown my invention in but one form, it will be obvious to those skilled in the art that it is not so limited but is susceptible of various other changes and modifications without departing from the spirit thereof, and I desire therefore that only such limitations shall be placed thereupon as are imposed by the prior art or as are specifically set forth in the appended claims.

Having thus described my invention what I claim as new and desire to secure by Letters Patent is:

1. An expansion joint for concrete pavement having separate slabs on opposite sides of the joint, interlocking means on said slabs to retain the slabs against vertical displacement, said interlocking means comprising a plurality of dovetail recesses on one of said slabs having the side wall thereof converging towards the bottom of the slab and a plurality of projections on the

- other of said slabs having their sides converging towards the bottom of the slab cooperating with the dovetail recesses.
2. An expansion joint for concrete pavement having separate slabs on opposite sides of the joint, interlocking means on said slabs adjacent the edge thereof, said means comprising a dovetail recess in one of said slabs, the entrance to said recess from the bottom of the slab being narrower than the interior of said recess and a projection on the other slab of substantially the same contour as the dovetail recess cooperating with said recess to retain the upper surface of said slab in proper alignment.
3. An expansion joint for a concrete pavement having separate slabs on opposite sides of said joint, interlocking means on said slabs adjacent the adjoining edges thereof, said means comprising a dovetail recess in one of said slabs having the side walls thereof converging towards the bottom of the slab and a projection on the other slab cooperating with said recess to retain the surface of said slabs in alignment while permitting lateral movement of the slabs relative to each other.
4. In combination with a concrete pavement, an expansion joint therefor, separate slabs on opposite sides of said joint, a compressible strip adjacent the vertical edges of said slabs, said strip comprising upper and lower portions within the same vertical plane and a plurality of laterally extending projections adjacent the lower portion of said strip, each of said projections comprising converging side walls and a wall connecting said side walls.
5. In combination with a concrete pavement, an expansion joint therefor, separate slabs on opposite sides of said joint, a compressible strip adjacent the vertical edges of said slabs, said strip comprising upper and lower portions within the same vertical plane, said lower portion having a plurality of undercut recesses therein, hollow laterally extending projections on said strip adjacent said recesses, each of said projections comprising downwardly converging side walls and an end wall connecting said side walls.
6. In combination with a concrete pavement, an expansion joint therefor, separate slabs on opposite sides of said joint, a compressible strip adjacent the vertical edges of said slabs, said strip comprising upper and lower portions within the same vertical plane, said lower portion having a plurality of undercut recesses therein, hollow laterally extending projections on said strip adjacent said recesses, each of said projections comprising downwardly converging side walls and an end wall connecting said side walls, said end wall comprising a member of substantially the size and shape of the undercut recesses.
7. A road strip for an expansion joint comprising a substantially straight longitudinal member of a compressible material having undercut recesses in its lower portion, and laterally extending projections of the same general contour in cross section as the undercut recesses connected to said strip adjacent said recesses, each of said projections comprising downwardly converging side members.
8. A road strip for an expansion joint comprising a substantially straight longitudinal member of a compressible material having undercut recesses in its lower portion, and laterally extending projections of the same general contour in cross section as the undercut recesses connected to the side of said strip adjacent said recesses, each of said projections comprising downwardly converging side members.
9. A road strip for an expansion joint comprising a substantially straight longitudinal member of a compressible material having undercut recesses in its lower portion, and laterally extending projections of the same general contour in cross section as the undercut recesses connected to the side of said strip adjacent said recesses, each of said projections comprising a flanged metallic member having downwardly converging flanges and a compressible member intermediate the flanges of said metallic member.
10. A compressible parting strip for concrete pavements having a series of undercut recesses along its length adjacent the bottom thereof and a plurality of hollow projections, having downwardly converging sides of substantially the same general contour in cross section as the undercut recesses connected to one side of said strip adjacent said recesses.
11. An expansion joint for concrete pavement having separate slabs on opposite sides of the joint, interlocking means on said slabs adjacent the edge thereof, said means comprising a recess in one of said slabs, the entrance to said recess from the bottom of the slab being narrower than the interior of said recess, and a projection on the other slab cooperating with said recess to retain the upper surface of said slab in proper alignment.
12. An expansion joint for a concrete pavement having separate slabs on opposite sides of said joint, interlocking means on said slabs adjacent the adjoining edges thereof, said means comprising a recess in one of said slabs having the side walls thereof spaced at a lesser degree adjacent the bottom of the slab than they are spaced a distance from the bottom of the slab and a projection on the other slab cooperating with the walls of said recess to retain the surface of said slabs in alignment while permitting lateral movement of the slabs relative to each other.
13. In combination with a concrete pavement, an expansion joint therefor, separate slabs on opposite sides of said joint, a road strip adjacent the vertical edges of said slabs, said strip comprising upper and lower portions within the same vertical plane and a plurality of laterally extending projections adjacent the lower portion of said strip and extending substantially to the bottom thereof, each of said projections comprising side walls having the lower portion thereof spaced at a lesser degree than the upper portion thereof and a wall connecting said side walls.
14. A parting strip for concrete pavements having a series of undercut recesses along its length adjacent the bottom thereof and a plurality of hollow projections having sides extending substantially to the bottom of the strip and the lower portions of which are spaced at a lesser degree than the upper portions thereof extending to the side of said strip adjacent said recesses.
15. A joint for a concrete pavement having separate slabs on opposite sides of said joint, means in said slabs adapted to retain the upper surface of the slabs in proper alignment, said means comprising a recess in one of said slabs, having its sides spaced a greater degree towards the top of the recess than at the bottom of said recess and means extending from the other slab into said recess and cooperating with the sides of said recess.
16. A road strip for an expansion joint com-

prising a longitudinal member having undercut recesses in its lower portion, the entrance to said recesses from the bottom of said member being narrower than the interior of said recesses, and laterally extending projections of substantially the same general contour in cross section as the undercut recesses connected to said strip adjacent said recesses, the bottom of said projections lying in substantially the same horizontal plane as the bottom of the strip.

17. In combination with a concrete pavement, a joint therefor, slabs on opposite sides of said joint, a road strip intermediate said slabs having

dovetailed recesses therein, one of said slabs having dovetailed recesses within the side walls thereof spaced a lesser degree towards the bottom of the slab than they are spaced towards the top of the slab, and means, comprising a member of substantially the same size and shape as the dovetailed recesses in said strip, cooperating with said strip and projecting into one of the recesses in the slab, said means cooperating with means associated with the other slab to retain the slabs against independent vertical displacement.

WILLIAM E. WHITE.
